FUEL CHARGE FORMING MECHANISM
 Walter W. Hamby, Smyrna, Ga., assignor to J. M. Feighery Company, Dalton, Ga., a corporation of Georgia
 Filed Aug. 19, 1963, Ser. No. 302,849
 10 Claims. (Cl. 123—127)

This invention relates to a fuel charge forming mechanism for a motor vehicle engine.

An important object of the invention is to provide a fuel charge forming mechanism, auxiliary to a conventional carburetor, for supplying fuel charges to a motor vehicle engine to greatly facilitate the acceleration of the engine, thus providing low-powered vehicle engines with a high degree of performance in accelerating from a standing start and for passing other vehicles.

A further object is to provide such a mechanism, a functioning part of which is arranged between a conventional carburetor and the intake manifold and which functions independently of the carburetor upon the depression of the accelerator pedal to its limit, to provide a pressure-supplied charge to the motor vehicle engine.

A further object is to provide a mechanism of the character just referred to wherein, in the normal operation of the vehicle engine, the device does not interfere with the normal functioning of the carburetor, the device being provided with a chamber through which the carburetor normally directly supplies fuel to the intake manifold.

A further object is to provide a device of the character referred to which, when operative, performs the function of supplying a continuous fuel charge to the motor vehicle engine while rendering the conventional carburetor substantially functionless.

A further object is to provide an auxiliary charge forming and supplying mechanism which, when caused to function by depressing the accelerator pedal to its limit of movement, supplies a continuous fuel charge under pressure and which rate of flow automatically increases as the engine speed increases, thus providing the engine with a high degree of accelerating power, far beyond that which can be attained by the normal functioning of the conventional carburetor.

A further object is to provide such a mechanism which functions wholly independently of the degree of vacuum developed by the engine whereby, in starting from a standstill at low engine speeds, efficient fuel charges are supplied while the vacuum developed by the engine is substantially negligible, the device at all times satisfying the volumetric requirements of the engine while supplying fuel proportioned to the engine speed to provide a surprisingly high degree of power at relatively low engine speeds, and which power increases rapidly as the engine speed increases.

Other objects and advantages of the invention will become apparent during the course of the following description.

In the drawings I have shown one embodiment of the invention. In this showing

FIGURE 1 is an elevation looking at the forward end of a motor vehicle engine showing the invention applied;

FIGURE 2 is a side elevation of the same, a portion of the motor vehicle engine being broken away;

FIGURE 3 is an enlarged detailed sectional view on line 3—3 of FIGURE 2;

FIGURE 4 is a plan view of the portions of the present mechanism directly associated with the engine manifold;

FIGURE 5 is a vertical sectional view on line 5—5 of FIGURE 4 showing a portion of the engine manifold and carburetor;

2

FIGURE 6 is an enlarged sectional view of line 6—6 of FIGURE 5;

FIGURE 7 is a vertical sectional view through a surge tank;

FIGURE 8 is a horizontal sectional view on line 8—8 of FIGURE 7, somewhat enlarged;

FIGURE 9 is a similar view on line 9—9 of FIGURE 7; and

FIGURE 10 is a perspective view of portions of the mechanism showing the electrical system associated therewith.

Referring to FIGURES 1 and 2, the numeral 10 designates a motor vehicle engine as a whole, which may be of the V-type as shown in FIGURE 1. On the forward end of crank shaft 11 is mounted a pulley 12 around which passes the usual belt 13 for driving the pulley 14 to which is connected a fan 15. Also mounted on the shaft 11 is a small pulley 16 for driving a belt 17 for a purpose to be described.

20 The engine is provided with the usual intake manifold 20 (FIGURES 1, 2 and 5), above which is arranged a conventional carburetor 21 having a venturi passage 22 controlled by a butterfly or throttle valve 23 mounted on a shaft 24 controlled by an arm 25. This arm is connected by the usual rods, linkages and levers indicated as a whole by the numeral 26 to an accelerator pedal 27 (FIGURE 2). The carburetor and its operating means may be conventional.

Ordinarily, the carburetor seats directly on the manifold 20. In the present case, a casing forming a part of the present invention and indicated as a whole by the numeral 30, is arranged between the carburetor and the manifold. This casing is provided with a portion 31 having horizontal top and bottom walls apertured respectively as at 32 and 33 and through which carburetor charges flow downwardly directly from the passage 22 through the usual top opening 34 of the manifold 20. It will become apparent that when the device of the present invention is not functioning, the carburetor 21 functions in its normal manner to provide a continuous fuel charge to the manifold 20 and thus to the engine.

One end of the casing 30 flares as at 36 to provide a cylindrical portion 37 forming an air passage 38 of substantial diameter opening into the chamber 39 (FIGURE 5) of the casing 30. The air passage 38 is normally closed by a throttle valve 40 mounted on a shaft 41 and having one edge portion engaging a limiting stop 42 as shown in FIGURE 5.

50 A spring 43 is connected to the free end of an operating arm 44 on the shaft 41, the other end of the spring being connected to a pin 45 fixed to the casing 30. This spring biases the valve 40 to the normally closed position shown in FIGURE 5.

The other end of the shaft 41 is provided with an arm 48 to the free end of which is connected one end of a link 49. The other end of this link is connected as at 50 to the adjacent end of the armature 51 of a solenoid 52 which, when energized, swings the arm 48 to turn the valve 40 to its fully open position shown in phantom lines on FIGURE 5.

At the end of the housing 30 opposite the air passage 38 is fixed a casting 55 secured to the casing 30 by screws 56. The outer end of the casting 55 is provided with a recess 57 (FIGURE 6), forming a chamber in cooperation with a pressure responsive diaphragm 58, biased to the left in FIGURE 6 by a spring 59. The right-hand end of this spring engages a seat 60 carried by an adjusting screw 61 provided with a lock nut 62. As described below, pressure is generated under certain conditions in the chamber 57 to move the diaphragm 58 against the loading of the spring 69, and this spring is adjustable by

loosening the nut 62, turning the screw 61 and tightening the nut 62. Obviously, the screw 61 is threaded through a yoke 63 and the ends of this yoke, together with the diaphragm 58, are secured to the casting 55 by the screws 56.

The casting 55 is provided with an axial extension 68 projecting through an opening 69 in the casing 30, into the chamber 39 (FIGURE 5). The casting 55 is provided with an axial passage 70 in which is axially movable a stem 71 secured at one end to the diaphragm 58 and provided at its other end with a conical valve 72 normally engaging a seat 73 formed in a plug 74 threaded in the end of the extension 68. An apertured bearing member 75 guides the end of the stem 71 adjacent the seat 73. Fuel is supplied to the passage 70 through a radial passage 76 to which is connected one end of a pipe 77, further referred to below.

Referring to FIGURE 2, the numeral 82 designates a conventional vehicle fuel pump having an inlet line 83 from the fuel tank of the vehicle and an outlet line 84 leading to a surge tank 85. This tank as shown in FIGURES 7, 8 and 9 is vertically arranged and provided near the top thereof with openings 86, 87 and 88, and near the bottom thereof with an opening 89. The pipe 84 is connected to one of the upper openings, in the present instance, the opening 86. The opening 88 is connected to one end of a line 92 leading to the carburetor 21 (FIGURE 5) to supply fuel thereto.

The opening 87 (FIGURES 7 and 8) is connected to one end of a fuel line 93 leading to a conventional solenoid operated three-way valve 94. This valve is connected to the pipeline 77 (FIGURE 4), and a third pipe 95 is connected to the three-way valve 94. The pipe 95 is normally open to the line 93 and closed to the pipe 77. When the solenoid of the valve device 24 is energized as described below, communication is closed from the pipe 95 to the pipe 93 and opened to the pipe 77.

A gear pump 100 having therein a chamber 101 and the usual gears 102 (FIGURE 3), is supported by a bracket 103 connected in any suitable manner to the vehicle engine. The pipe 95 is connected to the chamber 101 (FIGURE 3) to supply fuel from the latter to the three-way valve 94. The bottom opening 89 (FIGURES 7 and 9) of the surge tank is connected to one end of a pipe 105 to return fuel to the chamber 101 in a manner to be described.

The gears of the pump 100 are mounted on shafts 108 and 109, the latter of which rotates in a bearing 110 (FIGURE 2). The shaft 109 carries a pulley 111 about which passes the belt 17 to drive the pump 100 and maintain a fuel circulation as described below.

The electrical circuit for the mechanism is shown in FIGURE 10. A relay 115 is connected to source wires 116 and wires 117 and 118 extend to the accelerator pedal 27 shown as a switch in FIGURE 10. When the accelerator pedal is depressed to its limit, the circuit is closed across the wires 117 and 118 by engagement of the switch with a contact 119. This closes a circuit through wires 120 and 121 to energize the coil of the solenoid 52. Wires 122 and 123 are connected in parallel with the wires 120 and 121, and are connected to the coil of the three-way solenoid valve 94 so that both solenoids are energized when the accelerator pedal 27 is depressed to its limit.

Operation

The present invention functions only when it is desired to rapidly accelerate the vehicle from a standing start or when passing another vehicle. Assuming that the vehicle engine is operated under normal conditions, the conventional pump 82 supplies fuel through line 84 (FIGURES 2, 4 and 5) to the surge tank 85 from which fuel flows through pipe 92 to the carburetor 21. The carburetor functions conventionally in response to movements of the throttle valve 23 when the accelerator pedal is operated.

The mechanism of the present invention under the conditions being considered is inoperative. The valve 72 (FIGURE 6) will be closed and no fuel will be supplied past this valve to the intake manifold. The fuel charge from the carburetor will flow downwardly through the chamber 39 and through opening 34 into the intake manifold. While the present mechanism will not now be functioning, the gear pump 100 (FIGURES 2 and 3) will be constantly driven by the engine and fuel is supplied by the pump 82 to the surge tank through line 84. From this tank, through pipe 105, fuel will be supplied to the gear pump and will be pumped therefrom through line 95 to the three-way valve 94 and then through line 93 to the surge tank 85 to provide a constant circulation of fuel. The three-way valve 94 at this time will close communication between pipes 93 and 77. The only net flow of fuel from the tank 85 will be that demanded by the carburetor and this fuel is supplied, in accordance with the demands of the engine, from the pump 82.

Assuming that the vehicle is standing still and a rapidly accelerated takeoff is desired, or assuming that the driver desires to pass a vehicle ahead of him going in the same direction, he will depress the accelerator pedal to the limit, thus closing circuits through wires 120 and 121, and 122 and 123. This will energize the two solenoids and the solenoid 52 will rock the arm 48 to turn the valve 46 to the phantom line position shown in FIGURE 5, thus opening the chamber 39 to the free flow of air thereto independently of the carburetor. Such operation of the accelerator pedal also opens the carburetor throttle valve 23 to its maximum extent, under which conditions there will be a low degree of vacuum in the engine manifold, particularly if the vehicle is starting from a standstill. However, the present device will provide an adequate supply of fuel as described below.

The closing of the circuit through the solenoid valve 94 disconnects the pipes 95 and 93 and connects the pipe 95 to the pipe 77 to supply fuel through passage 76 (FIGURE 6) and to passage 70 and chamber 57. A build-up in pressure, acting against the diaphragm 58, will open the valve 72 and atomized fuel will be discharged around the valve 72 under pressure. This pressure will depend upon the adjustment of screw 61 and the volume is directly proportional to the engine speed. Initially, from the standstill, the engine speed will be relatively low and a relatively low rate of fuel discharge past the valve 72 will take place. This fuel, and the air supplied through air passage 38 into the chamber 39, will be sufficient to satisfy the volumetric requirements of the engine cylinder. A much more substantial fuel charge will be supplied to the engine than would be true in the normal operation of the carburetor.

With the accelerator pedal held depressed, the effective fuel charge supplied to the engine will increase as engine speed increases, since the gear pump 100 will be driven at increasing speeds and fuel will flow from the passage 70, past the valve 72 at an increased rate. It has been found that acceleration performance is greatly increased, and accordingly, the use of the present device is highly effective with older vehicles having engines of lower horsepower, and the so-called "compact" cars of relatively low horsepower. Such vehicles are thus provided with an acceleration performance comparable to that provided with vehicles having engines of high horsepower.

When the desired vehicle speed has been attained when starting from a standstill, or when the vehicle has passed another vehicle, the driver may release the accelerator pedal to any desired extent. Immediately upon breaking of the electrical circuits in FIGURE 10, the solenoid of the three-way valve 94 will be de-energized, under which conditions the pipe 95 will again communicate with the pipe 93 and will be cut off from the pipe 77. No more fuel will be supplied to the passage 70 (FIGURE 6) and the chamber 57, and the drop in fuel pressure in such chamber, will release the spring 59 to close the valve

72. The opening of the circuit through the solenoid 52 will release the spring 43 and the valve 40 (FIGURE 5) will be returned to normal position. Therefore, the present mechanism will cease to function and the controlling of the engine will be restored to the conventional carburetor 21.

It will be apparent that there is a continuous circulation of fluid through the gear pump 100 and surge tank 85 and pressure from the gear pump is ready at all times upon the connection of the pipe 77 to the pipe 95 to supply pressure to the passage 77. Such operation takes place simultaneously with the opening of valve 40 (FIGURE 5). Since fuel is atomized under pressure past the valve 72 when the present device is functioning, a very low vacuum in the intake manifold is all that is necessary to effect the flow into the manifold of an adequate fuel mixture to provide the vehicle engine with a highly efficient acceleration rate.

While the accelerator has been shown in FIGURE 10 as a switch engageable with a contact 119, in actual practice, the unit 119 as viewed in FIGURE 2 is preferably a microswitch mechanically engageable by the accelerator pedal when the latter is depressed to its limit of movement. In all ranges of movement of the accelerator pedal, except when the microswitch is closed, the carburetor 21 functions normally to control the supply of fuel to the vehicle engine.

It is to be understood that the form of the invention shown and described is to be taken as a preferred example of the same and that various changes in the shape, size and arrangement of the parts may be made as do not depart from the spirit of the invention or the scope of the appended claims.

I claim:

1. An auxiliary charge forming mechanism for a motor vehicle engine having an intake manifold and a carburetor, a casing arranged between the carburetor and the intake manifold and having a chamber therein open at the top and bottom to the carburetor and manifold, respectively, said casing having an air passage leading to said chamber, a normally closed air valve controlling said passage, a fuel atomizing nozzle projecting into said chamber, a normally closed fuel valve controlling said nozzle, a fuel passage leading to said nozzle, normally inoperative means for supplying fuel under pressure to said fuel passage, means biasing said fuel valve to closed position, a pressure responsive element exposed to pressure in said fuel passage for overcoming said biasing means to open said fuel valve, and means for simultaneously rendering said fuel supply means operative and for opening said air valve.

2. A mechanism according to claim 1 wherein said means for supplying fuel under pressure to said fuel passage comprises a pump driven by the motor vehicle engine and operative as engine speed increases for increasing the pressure of the fuel acting against said pressure responsive element to progressively open said fuel valve as engine speed increases to provide for the full flow of fuel supplied by said pump to said chamber.

3. A mechanism according to claim 2 provided with a normally open circulating system for fuel pumped by said pump, said means for simultaneously supplying fuel to said fuel passage and for opening said air passage comprising a device for closing said circulating system and supplying fuel from said pump to said fuel passage.

4. An auxiliary charge forming mechanism for a motor vehicle engine having an intake manifold and a carburetor, a casing arranged between the carburetor and the intake manifold and having a chamber therein open at the top and bottom to the carburetor and manifold, respectively, said casing having an air passage leading to said chamber, a normally closed air valve controlling said passage, a fuel atomizing nozzle projecting into said chamber, a normally closed fuel valve controlling said nozzle, a fuel passage leading to said nozzle, a fuel pump

driven by the vehicle engine, a surge tank, a three-way valve connected to the outlet of said pump and normally connected to said surge tank, a return pipe connected between said surge tank and the inlet of said pump, thus establishing a normal circulatory system for pumped fuel, a supply line connected between said three-way valve and said fuel passage, and means for simultaneously opening said air valve and operating said three-way valve to disconnect it from said surge tank and connect it to said supply line to supply fuel to said fuel passage.

5. A mechanism according to claim 4 wherein said three-way valve is solenoid operated, electromagnetic means for opening said air valve, said control means comprising parallel circuits for the solenoid of said three-way valve and for said electromagnetic means.

6. An auxiliary charge forming mechanism for a motor vehicle having an intake manifold and a carburetor, a casing arranged between the carburetor and the intake manifold and having a chamber therein open at the top and bottom to the carburetor and manifold, respectively, the casing being horizontally elongated and having an air passage at one end, a normally closed valve controlling said air passage, the other end of said casing being closed, an atomizing nozzle projecting through said end wall and terminating in said chamber and provided therein with a fuel passage, a normally closed fuel valve in said passage controlling said nozzle, a body carrying said nozzle and provided with a recess forming a fuel chamber communicating with said fuel passage, a diaphragm closing said fuel chamber and connected to said fuel valve, a spring biasing said fuel valve to closed position, and means for simultaneously opening said air valve and supplying fuel under pressure to said passage and to said fuel chamber to move said diaphragm and open said fuel valve to supply atomized fuel to said first-named chamber.

7. In combination with a motor vehicle engine having an intake manifold and a carburetor having a fuel passage and a throttle valve controlling such passage, an accelerator pedal connected to said throttle valve, a pipe for supplying fuel to said carburetor, a casing arranged between the carburetor and the intake manifold and having a chamber therein open at the top and bottom to the carburetor and manifold, respectively, said casing having an air passage leading to said chamber, a normally closed air valve controlling said passage, a fuel atomizing nozzle projecting into said chamber, a normally closed fuel valve controlling said nozzle, a fuel passage leading to said nozzle, normally inoperative means for supplying fuel under pressure to said fuel passage, means biasing said fuel valve to closed position, a pressure responsive element exposed to pressure in said fuel passage for overcoming said biasing means to open said fuel valve, and means operative upon predetermined movement of said accelerator pedal for simultaneously rendering said fuel supply means operative and for opening said air valve.

8. The combination according to claim 7 wherein said means for supplying fuel to said fuel passage comprises a pump driven by the motor vehicle engine and operative as engine speed increases for increasing the pressure of the fuel acting against said pressure responsive element to progressively open said fuel valve as engine speed increases to provide for the full flow of fuel pumped by said pump to said chamber.

9. The combination according to claim 8 provided with a normally open circulating system for fuel pumped by said pump, said means for simultaneously supplying fuel to said fuel passage and for opening said air passage comprising a device for closing said circulating system and supplying fuel from said pump to said fuel passage.

10. In combination with a motor vehicle engine having an intake manifold and a carburetor having a fuel passage and a throttle valve controlling such passage, an accelerator pedal connected to said throttle valve, a pipe for supplying fuel to said carburetor, a casing arranged

7
between the carburetor and the intake manifold and having a chamber therein open at the top and bottom to the carburetor and manifold, respectively, said casing having an air passage leading to said chamber, a normally closed air valve controlling said passage, a fuel atomizing nozzle projecting into said chamber, a normally closed fuel valve controlling said nozzle, a fuel passage leading to said nozzle, a fuel pump driven by the vehicle engine, a surge tank, a three-way valve connected to the outlet of said pump and normally connected to said surge tank, a return pipe connected between said surge tank and the inlet of said pump to establish a normal circulatory system for pumped fuel, a supply line connected between said three-way valve and said fuel passage, and means operative upon predetermined movement of said acceler-

5
tor pedal for simultaneously opening said air valve and for operating said three-way valve to disconnect it from said surge tank and connect it to said supply line to supply fuel to said fuel passage.
